ABSTRACT

Apparatus for taking up a web which has one rotary shaft, in turn a plurality of shafts for mounting the cores of the rotatably wound web extended radially in the perpendicular plane to the rotary shaft, and a device drives the shafts for mounting the cores so as to selectively rotate and stop them at equidistant circumferential positions.

FIG. 3

FIG. 4

APPARATUS FOR TAKING UP A WEB

BACKGROUND OF THE INVENTION

1. Field of the Invention

This invention relates to an apparatus for taking up a web, and more particularly to an apparatus for taking up a web adapted for readily replacing the wound web cores.

2. Description of the Prior Art

An apparatus for taking up a web after the web such as paper, plastic, metal, etc., is treated, is used in various technical fields, but in any field, this type of apparatus for taking up a web lowers its efficiency in the whole by the operation for replacing the core, that is, the operation of removing the core wound with the web and of mounting new vacant core.

SUMMARY OF THE INVENTION

It is, therefore, an object of this invention to provide an apparatus for taking up a web which readily replaces the core so as to improve the efficiency of the taking up step.

According to one aspect of this invention, there is provided an apparatus for taking up a web which comprises one rotary shaft for mounting the cores of the wound web which are rotatably provided on a plurality of shafts which extend radially in the vertical plane with the rotary shaft, and a device for driving the shaft for mounting the cores so as to selectively rotate or stop it at equidistant circumferential positions.

The other objects, features and advantages of this invention will become apparent from the following description taken in conjunction with the accompanying drawings.

BRIEF DESCRIPTION OF THE DRAWINGS

FIG. 1 is a side view of the apparatus of this invention.

FIG. 2 is a front view of the apparatus of FIG. 1.

FIG. 3 is a partially cut side view of the essential parts of the apparatus.

FIG. 4 is a plan view of a portion of the apparatus.

DESCRIPTION OF THE PREFERRED EMBODIMENT

Reference is now made to the drawings, which show one embodiment of the apparatus according to this invention.

The apparatus for taking up a web of this invention comprises a take-up unit 2 rotatable about one main shaft 1, in which unit 2, four shafts 21, 22, 23 and 24, for mounting the cores extend radially in the vertical plane with the main shaft 1. This take-up unit 2 may rotate intermittently 90 degrees around the axis of the main shaft 1 so that the respective shafts 21 to 24 are brought, in turn, to equidistant circumferential positions, particularly in sequence to a vertical upstanding position. In the apparatus of this embodiment, this intermittent rotation is conducted by a thick wheel 3 of a geneva gear and a follower 4, but may also be done by another means such as one cycle motor.

In FIGS. 2 and 3, the structural detail of the take-up unit 2 and its driving system are shown. A drive shaft 6 having a take-up shaft transmission gear 60 is supported by a frame 5 provided at the side of the apparatus, and the shaft 6 is driven by engaging a belt on the pulley 61 fixed to the drive shaft 6. A turret plate 7 is

fixed to the main shaft 1, and four take-up transmission shafts 81, 82, 83 and 84 are supported in parallel by the turret plate 7. To the take-up transmission shafts 81 to 84 are fixed take-up shaft rotary gears 91 to 94 engaging the take-up shaft transmission gear 60 and interlocking gears 11 to 14. The interlocking gears 11 to 14 are disposed in the take-up unit 2 and always in engagement with the take-up gears 25, 26, 27 and 28 of the end of the take-up shafts 210, 220, 230 and 240 fixed to the shafts 21 to 24 for mounting the core of the take-up unit 2. The take-up unit 2 has keep rollers 31, 32, 33 and 34 for winding the web onto the core mounted to the shafts 21 to 24 without looseness. Bearings 41 to 44 rotatably support the take-up shaft 210.

In the take-up unit 2 thus constructed, if the take-up shaft rotary gear 91 is engaged with the take-up shaft transmission gear 60, when the drive shaft 6 is rotated, the take-up transmission shaft 81 is rotated through the transmission gear 60 and take-up shaft rotary gear 91, and the take-up shaft gear 25 is rotated by the interlock gear 11 so that the shaft 21 for mounting the core fixed to the take-up shaft 210 is rotated.

Whereupon, the other shafts 22, 23, 24 for mounting the core are stopped. Then, if the core is at first mounted onto the shaft 21 for mounting the core in the above state so that the web is taken up thereon and when the taking-up is completed the web is cut out at the same time the main shaft 1 is rotated at an angle of 90° in the direction as shown by an arrow in FIG. 1 by the geneva gears 3 and 4, with the result that the take-up shaft rotary gear 94 is engaged with the take-up shaft transmission gear 60 so that the rotation of the drive shaft 6 is transmitted to the shaft 24 for mounting the core, shaft 24 moving to vertical upright position.

Here, in FIG. 1, the web brought to the right side together with the core, which is removed, where vacant core is installed. Whereupon, the shaft 24 already starts to take up the web so that the taking-up is continuously conducted.

Therefore, it is not necessary that a special step and time for replacing the web roll after completion of taking up occurs, so that the time of the taking-up step is greatly shortened.

The replacement of the core is conducted only if the core is pulled in the direction of the take-up shaft, and vacant core is not installed with sliding axially and accordingly the operation is very simple.

It should be understood from the foregoing description that since the take-up shafts are radially provided with respect to the main shaft of the turret so that this is rotated around the main shaft in the apparatus of this invention, the apparatus may be simply constructed so as to greatly improve the efficiency of the steps of the operation thereof.

What is claimed is:

1. Apparatus for taking up a web comprising: a horizontally disposed rotary shaft, a plurality of rotatable core mounting shafts extending radially in the vertical plane from said rotary shaft and rotatable as an array therewith about the axis of said rotary shaft, means for indexing said rotary shaft to dispose each core mounting shaft of said array at sequential equidistant circumferential positions and to dispose a selected shaft in vertical upright position, a driving mechanism, and

said indexing means further including means for operatively coupling said driving mechanism to said selected core mounting shaft at said vertical upright index position to permit take up of said web.

2. Apparatus as set forth in claim 1, wherein a geneva

gear wheel and follower are provided to rotate the rotary shaft about its axis from one index position to another.
